ABRAHAM NOVICK, OF NEW YORK, N. Y., ASSIGNOR TO F. L. SMITH MACHINE CO. INC., OF NEW YORK, N. Y., A CORPORATION OF NEW YORK.

MACHINE BRAKE.

1,426,092.

Specification of Letters Patent. Patented Aug. 15, 1922.

Application filed March 16, 1920. Serial No. 366,277.

To all whom it may concern:

Be it known that I, ABRAHAM NOVICK, a citizen of the United States, and resident of the city of New York, in the county of New York and State of New York, have invented certain new and useful Improvements in Machine Brakes, of which the following is a specification.

This invention relates to braking mechanism, and especially to that type of such mechanism as is most advantageously applicable to envelope and similar machines.

One of the objects of this invention is the provision of a simple and effective adjustable brake for stopping a machine quickly by preventing the continuance of the motion of the machine due to inertia, after the power has been cut off.

A further object of this invention is the provision of means for automatically disengaging the machine clutch to cut off the power from the machine whenever the brake is set, and for automatically releasing the brake whenever the clutch is thrown into engagement and the power thereby transmitted to the machine.

A further object of this invention is the provision of means which make possible the release of the brake by hand when the clutch is thrown out of engagement, at which time the automatic means operate to set the brake, said manually operated means being arranged to drop into inoperative position when the clutch is thrown into engagement.

To attain the above and other objects, I employ the mechanism shown in its preferred form in the accompanying drawings, in which,

Fig. 1 is a plan view of my invention showing the mechanism in brake-releasing and clutch-engaging position. Fig. 2 is a front view of the same. Fig. 3 is a front view similar to Fig. 2, the parts being shown in the clutch-releasing and brake-setting position. Fig. 4 is a vertical section on line 4-4 of Fig. 3. Fig. 5 is a plan view of the operating collar and of the parts directly engaging the same, in the position corresponding to that shown in Fig. 3.

The frame 1 of the machine to which my improved mechanism is attached, suitably supports the main shaft 2, which is driven through a clutch controlled pulley from a suitable source of power, said clutch, pulley, and source of power not being shown. Pulley 3, mounted on shaft 2 transmits the

power through belt 4 to the other parts of the machine, the web 5 of said pulley being located at a sufficient distance to one side of the middle of the rim of said pulley as to allow brake band 6 to engage the inner face 7 of said rim. One end of the annular brake band 6 is adapted to have pressure put thereon as by means of pin 8 suitably secured in brake lever 9, while the other end of said brake band merges with plate-like portion 10 and outstanding supporting arm 11. The plate 10 of band 6 has an open slot cut therein to allow the same to be passed around the cylindrical part 12 of guide 13. For supporting said guide, a stud 14, suitably fastened to frame 1, is provided. Flanges 15 and 16 are formed on opposite edges of cylinder 12 of guide 13, and serve to hold part of plate 10 of the brake band between them to prevent side slipping of said band, cylinder 12 serving to prevent outward radial movement of the plate end of the band, with respect to shaft 2.

A lug 17 projecting from flange 16 is threaded to movably hold adjusting screw 18 therein, lock nut 19 acting to secure said screw in adjusted position. Along the upper edge of plate 10, a post 20 is mounted, said post being arranged for vertical adjustment on loosening set screw 21. For pivotally supporting brake lever 9, outstanding arm 11 of brake band 6 carries stud 22 loosely mounted therein, the threaded end of said stud 22 being securely screwed into lever 9 for allowing said lever and stud to rotate as a unit about the axis of said stud. The lower part of lever 9 is bifurcated to form branches 23 and 24, while the upper end 25 is bent so that it terminates at a point directly over post 20 and is suitably slotted at 33 to receive hand lever 26, rotatable about pin 27 passing through slot 33, a second pin 28 being positioned in the end 25 and passing through slot 33 above pin 27 to limit the downward movement of lever 26 in one direction and the upward movement of said lever in the opposite direction.

Pin 27 is passed through said lever near one end thereof, so that the longer part normally drops down as far as pin 28 will allow. The shape of the smaller end of said lever is such that when said end is near enough to post 20, rotation of said lever about pin 27 causes the small end of said lever to fulcrum about the upper surface of post 20 to raise the end 25 of brake

lever 9. Branch 23 of lever 9 has spring rod 29 passing therethrough, spring 30 positioned between the head 31 of said rod and the end of branch 23 acting to force head 31 against the lower end of adjusting screw 18 and acting also to rotate lever 9 to a position where pin 8 of said lever presses the free end of brake band 6 as far as it will go into closely pressed contact with 10 surface 7 of pulley 3.

Prong 24 carries round headed bolt 32 thereon, by means of which, lever 9 may be rotated against the action of spring 30 to withdraw pin 8 from the free end of the 15 brake band, thereby releasing the pressure on said band. Said bolt 32 is operated by the rounded end 34 of bifurcated control lever 35, pivoted at 36 on supporting arm 37 of frame 1. For operating the clutch, not 20 shown, and the brake mechanism simultaneously with one motion of the control lever, said lever has the ends as 34 thereof confined in groove 38 of slidable collar 39 on shaft 2, one side 40 of said collar being tapered. 25 Said collar is so designed that the longitudinal movement in one direction necessary to disengage bolt 32 from lever 35, is sufficient to cause clutch fingers 41 to ride up on the cylindrical part of collar 39 (Fig. 5) to 30 disengage the clutch, and the longitudinal movement of said collar in the opposite direction necessary to engage the clutch by causing clutch fingers 41 to drop on to the conical part 40 of said collar, is sufficient 35 to cause the end 34 of lever 35 to engage bolt 32 to release the brake, as will be more fully described hereinafter.

The operation of my improved mechanism is as follows. It being assumed that the 40 machine is in operation, the various parts are in the position shown in Fig. 1. If it is now desired to stop the machine, control lever 35 is moved so that end 34 moves away from pulley 3 and off the head of bolt 32. Collar 39 is thereby moved along shaft 2 away from 45 pulley 3. Clutch fingers 41, which were in clutch engaging position, ride up from conical part 40 of the collar to the cylindrical part, disengaging the clutch. Resistance to 50 spring 30 having been removed by the movement of lever 35, said spring tends to expand, forcing the branch 23 of brake lever 9 away from lug 17 and causing said brake lever to rotate together with stud 22 through 55 a small angle in arm 11 of the brake band until pin 8 presses the free end of the brake band 6 tightly on to surface 7 of pulley 3 into the braking position. The positions that collar 39, lever 35, clutch fingers 41 and 60 bolt 32 assume at this time are shown in Fig. 5. Similarly, when the clutch is engaged on the proper movement of control lever 35, the 65 brake is released, the pressure of pin 8 on the end of the brake band being relieved by the return movement of the parts, brake

lever 9 being rotated in a direction opposite to that described above against the action of spring 30. In Fig. 2, the brake band 6 is shown completely disengaged from surface 7, but it will be understood that the distance 75 between said band and the inner surface 7 of the pulley is exaggerated for clearness.

It is often necessary to cause the machine to which a clutch is attached to move a very small amount at a time, as when adjusting 75 or repairing the machine, or when beginning a run. If, under these circumstances, the clutch is thrown into engagement, the machine is very likely to move too far before the clutch can be disengaged. A hand wheel 80 is therefore usually provided to turn the machine, but, with the use of my improved mechanism, the clutch being disengaged and the brake being therefore set when the hand wheel is to be used, I have made provision 85 for manually releasing the brake without throwing the clutch into engagement. The parts being in the position shown in Fig. 3, if hand lever 26 is now raised to the position shown by the dotted lines of Fig. 2, the small 90 end thereof fulcrums against post 20, which has been previously adjusted to the proper height, and the end 25 of brake lever 9 is raised a sufficient distance to cause said brake lever to rotate somewhat to draw pin 8 away 95 from the free end of brake band 6, relieving the pressure on said band sufficiently to release the brake.

The head of bolt 32 is moved somewhat, but not quite to the position it is forced to 100 assume when it contacts with the end of control lever 35. It being desired now to apply the power again to the machine, control lever 35 is moved to throw the clutch into engagement, the end 34 thereof thereby 105 coming into contact with bolt 32, said bolt is moved an additional short distance sufficient to rotate brake lever 9 to raise end 25 and hand lever 26 thereon and to disengage 110 said lever from post 20, the weight of the large end of said hand lever 26 being sufficient to cause said lever to drop back to its normal position.

Adjustment of spring 30 is obtained by 115 loosening lock nut 19 and by manipulating screw 18 until said spring exerts the desired pressure on brake band 6, after which lock nut 19 is again tightened.

What I claim is:

1. In a braking mechanism, a control 120 lever, a slidable collar operated by said lever, means actuated by said collar for setting said mechanism, and means for operating said mechanism independently of said control lever, adapted to be set into brake releasing position and arranged to drop automatically into its inoperative position on the manipulation of said control lever.

2. In a brake, a control lever, means operatively connected to said lever for setting 130

- 5 said brake, and a hand lever pivoted near one end thereof and operatively connected to said brake, arranged to be set into position for releasing said brake independently 5 of said control lever and to automatically drop into its inoperative position on the manipulation of said control lever.
- 10 3. In a braking mechanism, means for manually releasing a brake comprising a brake lever, a hand lever pivoted near one end thereof carried by said brake lever, and an adjustable fulcrum arranged to be engaged by the small end of said hand lever on the manipulation of said hand lever when 15 said brake lever is in the brake setting position.
- 15 4. In a braking mechanism, a brake band fixed at one end thereof, and outstanding arm near the fixed end and integral with 20 said band, a brake lever pivoted on said arm, a pin on said brake lever for engaging the free end of said brake band, a spring arranged between said brake lever and the fixed end of said brake band for urging said 25 brake lever toward the brake setting position, and a control lever for partly rotating said brake lever for setting and for releasing said brake.
- 25 5. In a braking mechanism, an annular 30 brake band terminating in a slotted plate-like portion, means arranged in the slot of said band for fixedly holding said plate-like portion, an arm outstanding from the fixed portion of said band, a spring pressed
- 35 brake lever pivotally mounted on said arm, and a pin in said brake lever for engaging the free end of said brake band.
- 40 6. In a braking mechanism, an annular brake band terminating in a plate-like portion, means for preventing radial outward movement of said plate-like portion, an arm outstanding from said plate-like portion, a spring pressed brake lever carried by said arm, a pin in said brake lever engaging the free end of said brake band, means for 45 partly rotating said brake lever for setting and for releasing said brake, a hand lever pivoted near one end thereof carried by said brake lever, and an adjustable fulcrum arranged to be engaged by the small end of 50 said hand lever on the manipulation of said hand lever when said brake lever is in the brake setting position.
- 45 7. In a braking mechanism, a control lever, a slideable collar operated by said lever, 55 a brake band, a brake lever carried by said band, a pin on said brake lever for engaging the free end of said band when said control lever is moved out of operative engagement with said brake lever, a spring urging said 60 brake lever pin into brake setting position and manually operable means for releasing said brake band against the action of said spring, independently of said control lever.

Signed at the city of New York, in the 65 county of New York and State of New York, this 8th day of March, A. D. 1920.

ABRAHAM NOVICK.
